UNITED STATES PATENT OFFICE.

GEORGE W. SPALDING, OF WORCESTER, MASSACHUSETTS, ASSIGNOR TO UNIVERSAL PATENTS COMPANY, A CORPORATION OF RHODE ISLAND.

WOVEN CARRIER.

1,275,489.

Specification of Letters Patent. Patented Aug. 13, 1918.

Application filed April 11, 1917. Serial No. 161,110.

To all whom it may concern:

Be it known that I, GEORGE W. SPALDING, a citizen of the United States, residing at Worcester, in the county of Worcester, State of Massachusetts, have invented a certain new and useful Improvement in Woven Carriers, of which the following is a specification, reference being had therein to the accompanying drawings.

10 The invention has relation to pocketed carriers made of woven material, namely carriers on the order of those which are used for holding and carrying cartridges, packaged first-aid supplies, etc. Among the 15 pocketed carriers to which the invention is applicable are comprised cartridge-carriers, hospital corps belts, medical officers' belts, and others having special adaptations.

More particularly, the invention relates 20 to the flexibly attached covers which are provided in connection with the pockets of carriers of the said general class. It is in the nature of an improvement upon so-called box-covers or hoods on the order of 25 those which are shown, described, and claimed in the U. S. Letters Patent to F. R. Batchelder for woven carriers, No. 1,211,275, dated Jan. 2, 1917. As in the case of the invention presented in the said patent, the 30 present invention has for its general object the production of a practical improved flexibly attached box-cover or hood which shall afford complete protection for the contents of the pocket with which it is combined, 35 that is to say by effectually excluding moisture, mud, sand and dust; which shall insure effectually against the escape of articles (as for instance, cartridges in the case of a cartridge-carrier); and which shall be of a 40 construction enabling the drawbacks or disadvantages of woven material to be avoided or be taken care of properly.

The invention provides a box-cover or hood on the order of that of the patent 45 aforesaid, comprising essentially a one-piece blank, and characterized by having a front with opposite lateral flanges which are lapped outwardly around the forward margins of the sidewings and secured 50 against the outer faces of the side-wings.

The drawings illustrate embodiments of the invention.

Figure 1 is a perspective view showing two of the pockets of a woven carrier, the

said pockets having combined therewith 55 box-covers or hoods made in conformity with the invention.

Fig. 2 is a plan of a woven blank which may be employed in making a box-cover or hood on the order of those shown in Fig. 1. 60

Fig. 3 is a perspective of a woven blank which is produced in a so-called folded state.

Fig. 4 is a perspective of a portion of a continuous web comprising a series of folded blanks like that shown separately in Fig. 3. 65

Fig. 5 is a face or plan view of the said continuous web.

The body or band-portion 1 of the carrier shown in Fig. 1, and the pockets 2, 2, thereon, are formed of flexible woven material, and may be produced integral with each other by proper procedure in weaving, which is regarded as preferable, although in some cases they may be formed separately and fastened together in approved manner. 70 The carrier may be furnished with one pocket, only, or with a plurality of pockets, according to the purpose which the carrier is designed to serve. In Fig. 1, in which the cover or hood of one of the pockets is shown 75 raised, the corresponding pocket is represented, by way of illustration, as filled and expanded by packages 3, 3, such as commonly contain the supplies that are furnished to the hospital corps. The filled 80 pockets in this instance are substantially 85 rectangular in cross-section.

Referring briefly to the leading features, in general, of the pocket-covers or hoods:

For the purpose of enabling a pocket-cover or hood to be secured in place in proper relations with the pocket with which it co-operates, the said cover or hood is provided with a downward extension 4 from its top, which extension is made fast in some 90 approved manner at the back of the pocket. For example, it may be inserted into a housing slit 1^a provided in the upper portion of web 1, as shown in Fig. 1, and be secured in the said slit by means of stitches 1^b or other convenient fastenings in practice. The 95 employment of the housing-slit is preferred, but is not indispensable.

The top of the cover, flap, or hood is marked 5. The two side-portions, wings, or 100 skirts are marked 6, 6. The front is marked 7. As usual, fastening means are provided for holding the cover, flap, or hood securely

closed when required, as at the right in Fig. 1. The drawings show means of ordinary character, comprising a stud 11, applied to and projecting from the front wall of the 5 pocket, and a coöperating socket 12 applied to the front 7 of the cover, flap, or hood.

The characteristic and essential feature of the invention is the fact that the cover, flap, or hood, consisting of a one-piece blank, 10 has integral opposite lateral flanges x , x , Fig. 1, preferably selvaged, which are lapped around the forward margins of the side-wings or skirts 6, 6, and lie flatwise against the outer surfaces of said side-wings 15 or skirts, to which they are secured in convenient manner. In the illustrated embodiment of the invention the securing is effected by means of stitches 9, 9.

The blank for the cover, flap, or hood, is a 20 one-piece blank of woven material, one example of the same being represented in Fig. 2 and another in Fig. 3. The blank shown in Fig. 2 is formed with the comparatively narrow rear section 4^a, constituting the rearward attaching extension 4 of the made-up box-cover, flap, or hood. Also with a middle section 5^a constituting the top 5 of the made-up cover, flap, or hood and having opposite lateral projections 6^a, 6^a, which constitute 25 the side-portions, wings, or skirts 6, 6, of the cover. Also with a forward section 7^a constituting in the finished cover, flap, or hood the front 7 thereof. In accordance with the invention, this forward section is furnished 30 with opposite lateral widenings x' , x' , as shown, which in the flattened-out state of the blank render the total width of the forward section greater than that of the rearward section. The relative difference in 35 width is not material. The particular blank shown in Fig. 2 is produced by the operations of weaving, following established methods of procedure, and with firm woven 40 selvages at the opposite sides of the narrow section 4^a for the rearward extension, also at the lateral edges of the two wing-projections 6^a, 6^a, for the side-wings or skirts 45 at opposite sides of the top, and also at opposite lateral edges of the laterally-widened 50 section 7^a for the front 7, said last mentioned section being somewhat narrower than the section comprising the top and side-wings, but somewhat wider than the section for the rearward extension.

55 In weaving the one-piece blank shown in Fig. 2 the warp-threads that are utilized in the formation of the lateral projections 6^a, 6^a, for the side-wings or skirts, but not in the formation of the section 4^a for the 60 rearward extension of the cover, flap, or hood, are floated alongside the said rearward section 4^a, without interweaving them with the weft-threads until the beginning of the lateral projections is reached. Upon 65 the completion of the section comprising the

top and lateral projections, and during the weaving of the section 7^a for the front of the hood or cover, certain of the warps which were floated alongside the rearward section are interwoven with the weft-thread to form 70 the lateral widenings x' , x' , of the section 7^a. The remainder of those warp-threads which were floated during the production 75 of the rearward section and which are not required in the production of the lateral widenings x' , x' , of the front section, are also floated alongside such widenings without being interwoven with weft-thread. In practice, a continuous series of the blanks 80 will be woven in succession, united in the form of a web in the weaving, and will be separated from one another by cutting across the said web at the proper points for dividing up the web into individual blanks.

The floated warp-threads will be trimmed 85 off. As thus produced, the rearward section of the blank, the lateral projections of the intermediate section, and the lateral widenings of the front section, will have firm woven selvages.

In making a blank like that of Fig. 2 up into a box-cover or hood, the lateral projections 6^a, 6^a, of the blank, and the front section 7^a thereof are bent down at right-angles 95 to the top section 5^a, and the lateral widenings x' , x' , of the said front section are bent in the form of flanges around the front edges of the side-wings and are lapped against the outer surface of the said side-wings, being secured thereto by suitable 100 means, preferably by means of stitches 9, 9.

By folding the lateral widenings of the front in the form of flanges around the cut or raw front edges of the side-wings, such edges are covered and concealed. As a 105 result of making the said lateral widenings with selvages, turning or hemming of the flanges is rendered unnecessary. Consequently the flanges lie snugly and flatly against the outer surfaces of the side wings, 110 the side seams are flat and have no objectionable thickness, projecting ridgy joints or seams are avoided, and a smooth and acceptable finish is produced.

The lower end of the front 7 is finished off 115 in customary manner. The cut or raw rear edges of the side-wings or skirts 6, 6, are turned to the inner sides of the latter as at 6^b, Fig. 1, and stitched in place so as to conceal the said edges.

If deemed advisable, the weaving may be so conducted, by the employment of separate sets of warp-threads for the production of the lateral widenings x' , x' , of the blank shown in Fig. 2, as to leave the said widenings unconnected with the lateral projections 6^a, 6^a, at the ends of the said widenings adjoining the said lateral projections. In such case, the separate sets of warp-threads employed as just stated in the pro- 120 125 130

duction of the lateral widenings x' , x'' , will be floated from one pair of the said widenings to the next pair in the length of the continuous web, and will be trimmed off 5 subsequent to the weaving.

The form of blank shown in Fig. 3 is produced in a folded state by the weaving operations, as a part of a continuous web in which similar blanks succeed one another, as 10 for instance after the manner indicated in Figs. 4 and 5. In the said folded state, the lateral widenings are produced as flanges x^2 , x^3 , turned inwardly toward each other at the opposite sides of the front section 7^c 15 of the blank, and the lateral projections 6^c, 6^c, for the side-wings or skirts of the cover, flap, or hood overlap each other transversely of the blank.

In the case of the continuous web which 20 is shown partly in Figs. 4 and 5, double-length front sections 7^c alternate with double-length rear-extension sections 4^c, between the successive pairs of lateral projections 6^c, 6^c, and the web is separated into 25 individual blanks by cutting across it on the lines $y-y$ and $y-y$ at midlength of the respective double front-sections 7^c and double rear-extension sections 4^c.

Copies of this patent may be obtained for five cents each, by addressing the "Commissioner of Patents, Washington, D. C."

What is claimed as the invention is,—

1. A pocketed woven carrier having a 30 box-cover or hood furnished with side-wings comprising essentially a one-piece blank, and characterized by having a front with opposite lateral widenings which are folded in the form of flanges outwardly 35 around the forward margins of the side-wings of the cover or hood and secured against the outer faces of the side-wings.

2. A pocketed woven carrier having a box-cover or hood comprising essentially a 40 one-piece blank formed with a selvaged rear section which is attached to the back of the pocket, an intermediate section comprising a top and selvaged side-wings, and a front section with opposite lateral widenings 45 which are folded in the form of flanges outwardly around the forward margins of the said side-wings and secured against the outer faces of the side-wings.

In testimony whereof I affix my signature 50 in presence of two witnesses.

GEORGE W. SPALDING.
